SAMUEL DARLING AND JOHN E. HALL, OF BANGOR, MAINE.

Letters Patent No. 76,719, dated April 14, 1868.

IMPROVEMENT IN INKSTANDS.

The Schedule referred to in these Letters Patent and making part of the same.

TO ALL WHOM IT MAY CONCERN:

Be it known that we, SAMUEL DARLING and JOHN E. HALL, both of Bangor, in the State of Maine, have invented certain Improvements in Inkstands; and we do hereby declare that the following, taken in connection with the drawings which accompany and form part of this specification, is a description of our invention sufficient to enable those skilled in the art to practise it.

The object of our invention is so to construct an inkstand and a pen-rack, as that when the person has done writing, the mere act of laying down the pen shall of itself cover the mouth of the stand, and keep it covered until the pen is again taken up, the removal of the pen causing the mouth to be again uncovered.

It consists in the employment, in connection with an inkstand, of a pivoted pen-rack, to which a cover is attached, the rack being so balanced, or weighted, or otherwise, that the weight of the pen or a slight touch of the rack will close the mouth of the inkstand.

In the accompanying drawings—

Figure 1 represents a top view, and

Figure 2 a side view of an inkstand embodying our invention.

A is the inkstand, which may be of any desired form. B is a base or platform, which it is found desirable to construct so that it shall sustain upon it both the stand and a pen-rack support, C.

It is preferable that the inkstand shall merely rest on the base by its own weight, so as to be easily removed, if desired, but it may be secured thereto. When not secured, it is better that it should rest in a shallow socket in the base, or within a band or ring thereon. In fig. 1, the pen-rack is shown as pivoted to the base at the points D E, and then rising and having two arms F G, at sufficient distance apart to allow a pen, P, to lie thereon in a horizontal plane. These arms are bent, as shown, so as to pass over to the opposite side of the inkstand, and then curve downward, so as not to incommod the writer when the inkstand is in use; a slight curvature upwards at their outer free ends, or any equivalent provision, serving to receive and sustain the pen when deposited there.

A cap or cover, H, for the mouth of the inkstand, and which may be made of any suitable form adapted to the style of mouth of the inkstand used, is shown in the drawings as a simple disk, slightly dished, with its concave side downwards. This cap is secured to an arm, I, projecting from the pen-rack, and in such position relatively to the mouth of the inkstand, that when the weight of the pen is on the rack, and bears it down, the cap will closely cover the mouth, and when the pen is removed, the cover will rise and recede from the mouth, by reason of a sufficient counterbalancing weight previously determined, and given to the rack at its rear. The rack should be centred on its axis or pivots, so that in its normal position, the heavier but shorter arm of the lever will always carry the cover away from the mouth.

1. We claim a swinging pen-rack, so combined with the cover of an inkstand, that the movement of the rack will operate the cover.

2. We also claim the combination, with an inkstand and its cover, of a pen-rack, or its equivalent, in such manner that the mere weight of the pen-holder, when laid down by the writer, shall cause the ink to be covered, and that the ink shall be uncovered when the pen is taken up.

SAMUEL DARLING,
JOHN E. HALL.
